INDOOR TELEVISION ANTENNA

Marvin P. Middlemark, 96 Store Hill Road,
Old Westbury, N.Y. 11568

Filed Dec. 23, 1974, Ser. No. 535,219

Term of patent 14 years

Int. Cl. D14—03

U.S. Cl. D26—14 F

FIG. 1 is a front perspective view of an indoor television antenna showing my new design;

FIG. 2 is a side elevational view thereof; and

FIG. 3 is a rear elevational view thereof.

I claim:

The ornamental design for an indoor television antenna, as shown.
